Charles C. Gill,
ATTORNEY.

UNITED STATES PATENT OFFICE.

WALTER ROTHENBERG, OF BROOKLYN, NEW YORK, ASSIGNOR TO HENRY HYMAN & CO.
INC., OF NEW YORK, N. Y., A CORPORATION OF NEW YORK.

DESIGN FOR AN EMBLEM.

52,046.

Specification for Design.

Patented May 14, 1918.

Application filed February 18, 1918. Serial No. 218,000. Term of patent 7 years.

To all whom it may concern:

Be it known that I, WALTER ROTHENBERG, a citizen of the United States, residing at Brooklyn, in the county of Kings and State of New York, have invented a new, original, and ornamental Design for an Emblem, of which the following is a specification, reference being had to the accompanying drawings, forming a part thereof, and which presents a face view of an emblem embodying my design.

I claim:

The ornamental design for an emblem, as shown.

WALTER ROTHENBERG.

Witnesses:

ARTHUR MARION,
CHAS. C. GILL.
